UNITED STATES PATENT OFFICE.

BENJAMIN FRANKLIN SWEZEY, OF BELLINGHAM, MINNESOTA.

DEVICE FOR PREVENTING SNOW-DRIFTS.

1,108,943.

Specification of Letters Patent.

Patented Sept. 1, 1914.

Application filed January 4, 1913. Serial No. 740,228.

To all whom it may concern:

Be it known that I, BENJAMIN F. SWEZEY, a citizen of the United States of America, residing at Bellingham, in the county of Lac 5 qui Parle and State of Minnesota, have invented certain new and useful Improvements in Devices for Preventing Snow-Drifts, of which the following is a specification, reference being had therein to the accompanying drawing.

This invention relates to means for keeping railroad cuts free from snow drifts and the like, and has for its object the production of a simple and efficient means which 15 may be placed upon the banks of the cut in such a manner as to drive the snow from the cut and cause the snow to be blown beyond the same.

Another object of this invention is the 20 production of a simple and efficient shield or deflector which may swing from side to side so as to accommodate itself to the direction in which the wind is blowing.

With these and other objects in view, this 25 invention consists of certain novel constructions, combinations and arrangements of parts, as will be hereinafter fully described and claimed.

In the drawings:—Figure 1 is a perspective view of a portion of the railroad cut showing the manner in which the wind shields are mounted upon the banks of the cut. Fig. 2 is a sectional view through the cut showing the deflectors in side elevation. 35 Fig. 3 is a detail perspective of one of the deflectors, and Fig. 4 is a top plan view of one of the deflectors.

By referring to Fig. 1, it will be seen that the deflectors are mounted in a series along 40 the sides of the railroad cut in such a manner as to cause the wind, when blowing across the cut, to strike the deflectors and follow the course of the cut along the bottom thereof and drive the snow or other accumulated matter up on the adjacent bank.

A plurality of anchoring posts 1 are placed along the edge of the bank, and within these anchoring posts are secured supporting rods, journal portions or standards 50 2, having collar portions 3 formed thereon to limit the downward movement of the journal portions 2 relative to the anchoring posts 1. A shield supporting head 4 is carried by each standard 2 and this shield supporting head is rigidly fixed upon the standard. The shield supporting head 4 is pro-

vided with an upwardly extending centrally arranged boss 5 which constitutes an abutment for the cross shield supporting arm 6. The rear ends of the shield supporting arms 6 are bent downwardly, as indicated at 7, so as to project through the reduced ends 8 of of the head 4, and nuts 9 are threaded on the ends to constitute means for holding the arms 6 in engagement with the boss 5. The forward ends of the supporting arms 6 are bent upwardly to constitute shield supporting fingers 10, and upon these shield supporting fingers 10 is journaled the shield 11. This shield 11 is provided near its upper and lower corners with a plurality of rolled portions 12, which constitute means for gripping the fingers 10, whereby the shield will be firmly held in engagement with the fingers 10. The side edges of the 75 shield 11 extend rearwardly, as indicated at 13, to constitute a broad wind engaging portion, so as to allow the shield to be freely acted upon and swung by the wind coming in contact therewith.

From the foregoing description, it will be seen that owing to the fact that the shield 11 is so mounted upon the anchoring post 1 and standard 2, the shield 11 may swing to any desired angle so as to accommodate 85 itself to any direction in which the wind is traveling, whereby the wind will be driven down through the bottom of the cut for driving the snow or other accumulated substance from the cut. Of course, it should 90 be understood that where the snow is being carried in drifts, the snow will strike against the rear faces of the deflectors 11 and will be thrown upon the sides of the bank and prevented from falling upon the track. If, 95 however, the snow should so fall upon the track, the wind, by constantly blowing and causing a downward air current, will drive the snow up the opposite bank and keep the track clear for the passage of trains. Of 100 course, it should be understood that as many of these deflectors as are illustrated in Fig. 1 may be used, only four being shown for the purpose of illustration in the present instance.

From the foregoing description, it will be seen that a very simple and efficient device has been produced, whereby considerable labor will be saved on the part of the railroads and the like wherein it is necessary 110 to clear the cuts from the snow in order to allow traffic to pass therethrough. By em-

ploying the device as illustrated in the present application, it should be understood that the necessity of employing manual means for clearing the cuts will be eliminated, owing to the fact that the shields as set forth will constitute automatic means for keeping the cuts clear and clean from snow drifts or other accumulated substances. Of course, it should be understood that the present device may be applied to road cuts other than railroad cuts and still perform the same function as described with reference to a railroad cut.

Having thus described the invention, what is claimed as new, is:—

1. A device of the class described comprising a support, a wind shield and a plurality of supporting arms secured to said wind shield and adapted to swing from side to side relative to said support, whereby said shield may be brought in efficient engagement with the wind according to the direction in which the wind is traveling.

2. The herein described means for preventing the accumulation of snow in railroad cuts comprising an anchor member, a shield and a plurality of supporting arms engaging said shield, said arms being loosely mounted on the latter for facilitating the swinging of said shield from side to side.

3. A device of the class described comprising an anchor post, a supporting standard, a head rotatably mounted upon said supporting standard, a wind shield and a plurality of supporting arms secured to said wind shield and head and loosely mounted

on the latter for facilitating the swinging of said shield from side to side.

4. A device of the class described comprising an anchor member, a supporting standard, a head securely mounted thereon and provided with a central boss portion, a plurality of arms journaled on the head and a shield, said arms being provided with upwardly extending outer ends engaging said shield, said shield being provided with a plurality of rolled ears fitting over said upwardly extending ends, and said arms being adapted to facilitate the swinging of said shield from side to side.

5. A device of the class described comprising an anchor member, a supporting standard, a head fixedly mounted thereon and provided with a central boss portion, a plurality of arms journaled on the head and a shield, said arms being provided with upwardly extending outer ends engaging said shield, said shield being provided with a plurality of rolled ears fitting over said upwardly extending ends, said arms being adapted to facilitate the swinging of said shield from side to side and said shield being provided with rearwardly extending portions constituting broad wind engaging wings.

In testimony whereof I hereunto affix my signature in presence of two witnesses.

DR. BENJAMIN FRANKLIN SWEZEY.
